UNITED STATES PATENT OFFICE.

JOHN W. DWIGGINS, OF ANDERSON, INDIANA, ASSIGNOR TO THE DWIGGINS WIRE FENCE COMPANY, OF SAME PLACE.

WIRE-FENCE MACHINE.

SPECIFICATION forming part of Letters Patent No. 595,291, dated December 14, 1897.

Application filed January 21, 1897. Serial No. 620,005. (No model.)

To all whom it may concern:

Be it known that I, JOHN W. DWIGGINS, a citizen of the United States, residing at Anderson, in the county of Madison and State of Indiana, have invented certain new and useful Improvements in Wire-Fence Machines; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to improvements in wire-fence machines of the class adapted to be operated by power other than hand-power for the purpose of weaving a series of wire pickets into a series of longitudinal wires, thereby producing woven wire fencing.

20 The objects of my invention are, first, to provide a means in a wire-fence machine for automatically reversing the movement of the twister-wheels, so as to alternate the direction of the twist in the wires between the pickets; second, a means for automatically carrying the horizontal wires forward, after a twist is formed therein, a sufficient distance to receive another twist; third, a means for automatically holding the horizontal wires in engagement with the twister-wheels while the twists are being formed; fourth, a means for automatically bringing the twister-wheels into contact with the horizontal wires; fifth, a means for automatically reeling the woven fencing into suitable rolls; sixth, a means for regulating the tension of the reel on the woven fencing while being reeled; seventh, a means for holding the pickets in place at an equal distance apart while being carried to the twisters; eighth, a means for lifting the pickets out of the picket-holders after passing the twisters; ninth, a means for properly tensioning and spacing the horizontal wires, and, tenth, to provide a machine that will be positive in its operation, easy to operate, and capable of producing a perfect wire fencing rapidly at small expense for attendants.

45 The further objects and advantages of my

improved wire-fence machine will be explained hereinafter.

My invention consists in the construction, combination, and arrangement of the machine and various parts thereof, which are described in the following specification and more particularly pointed out in the claims.

In the drawings, Figure 1 is a perspective view of my machine, showing the rear and right-hand side. Fig. 2 is a vertical sectional view of the reel and reel-tension device. Fig. 3 is a vertical sectional view of the carrier, sprocket-wheels, and star feed-arms. Fig. 4 is a top plan view of the machine, the upper framework being broken away. Fig. 65 5 is a detached perspective view of the device whereby the horizontal wires are held in engagement with the twister-wheels while being twisted. Fig. 6 is a plan view of one of the picket-holding bars attached to the sprocket-chain. Fig. 7 is an enlarged view of one of the wire-tension devices. Fig. 8 is an enlarged front plan view of one of casings holding the twister-wheels. Fig. 9 is an enlarged view of the twister-wheels and casing, 75 showing their attachment and connection with other parts. Fig. 10 is a vertical sectional view of the machine, taken on the line 10 10 of Fig. 4. Fig. 11 is a view of the main shaft, showing various parts mounted thereon. Fig. 12 is a top plan view of the movable frame carrying the twister-wheels. Fig. 13 is an enlarged top plan view of the mechanism for reversing the movement of the twister-wheels. Fig. 14 is a side view of the pivotally-mounted lever which operates the clutch by which the movement of the twister-wheels is reversed. Fig. 15 is a plan view of the left-hand side of the machine. Fig. 16 is a view of the shaft carrying cams for raising and lowering the frame carrying the twister-wheels. Fig. 17 is a side elevation of the device whereby the woven fencing is prevented from lifting out of the picket-holders until it reaches the carrier which lifts it out and passes it to the reel. Fig. 18 is an end elevation of Fig. 17. Fig. 19 is an edge view of the trip-lever mounted on the main shaft.

These views I deem necessary to properly show my invention, and like letters or fig-

ures of reference in the different views shown in the drawings refer to like parts.

The frame of the machine consists of uprights A and A', cross-pieces B and B', and supports C and C'. Upon this framework are mounted the various parts composing the complete machine. The power is applied to the band-wheel a, which is loosely mounted on a short shaft b. A friction-clutch c, having 10 the lever c', is also mounted on said shaft b and is adapted to engage the projecting hub d on the band-wheel a. Upon the shaft b is mounted a small cog-wheel e, and upon its inner end is also mounted a small bevel-gear f, which meshes with loosely-mounted bevel-gears f' and f'' upon a shaft D. Immediately 15 below the shaft b is a short shaft b', upon one end of which is mounted a large cog-wheel e', which meshes with the small cog-wheel e above it. Upon the opposite end of said shaft b' is mounted a small bevel-gear f''', which 20 meshes with the large bevel-gear f''', mounted on the shaft E. Upon the shaft E (shown detached in Fig. 11) are also mounted a wheel 25 g, having an eccentric groove formed in its outer rim or periphery, said groove extending entirely around its circumference, a sprocket-wheel h, a trip-arm i, and two operating-arms j, provided with small flat-faced 30 rollers k, journaled in each end thereof. Said shaft E is suitably mounted upon the frame. Upon a bar l, secured at each end to the framework, is provided a bent lever m, which is best seen in Figs. 13 and 14, said lever being 35 provided with a small roller k', adjustably mounted near one end, said roller being adapted to enter and travel in the groove in the wheel g. Near the opposite end the lever has a half-twist, which brings the flat sides at 40 right angles to the flat sides of the end carrying the roller k'. On said opposite end is formed a fork n, which engages a groove o in a sliding collar p, which is mounted on the shaft D between the bevel-gears f' and f''. 45 The collar p is provided with teeth r on either end, which engage with teeth r' on the hubs of the bevels f' and f''. The eccentric groove in the periphery of the wheel g, in which the roller k' travels, imparts an oscillating movement to the lever m, which serves to slide the collar p backward and forward slowly on the shaft D, causing it to alternately engage the bevels f' and f'', and thereby reverse the movement of said shaft. Upon the outer 50 end of the shaft D is fixedly mounted an eccentric wheel s, which is provided with projecting ears t and t'. The trip-lever i, which is formed with one arm of greater length than the other, has small rollers k'' mounted on 55 each end thereof. These rollers are adapted to alternately strike the ears t and t', which checks the movement of the shaft D and allows the collar p to slide freely without binding, as would be the case were it to travel under 60 tension. The collar p is held from turning on the shaft D by means of a key in the shaft, the collar being grooved to fit over the key. The

long end of the lever strikes the ear t and the short end the ear t', thereby giving a tension-trip for both the bevels f' and f''. A further 70 tension for the shaft D is provided by means of the friction-bearing F, which is regulated by means of a coil-spring G and nut u. The shaft D extends the full width of the framework, and between the cross-pieces B B has a suitable number of bevel-cogs v mounted thereon and adjustably secured thereto by means of set-screws. The twister-wheel frame H is pivoted between the cross-pieces B B and is so placed that the bevel-cogs v, mounted on the ends of the shafts I, will mesh with the cogs v on the shaft D. On the opposite ends of the shafts H are mounted the twisters J, of ordinary construction, enlarged views of which, Figs. 8 and 9, show 80 their construction and manner of attachment to the frame H. The twisters consist of a plain cog e² and a slotted cog e³, mounted in casings which are provided with slots o'. A shaft K (shown detached in Fig. 16) is mounted against the front uprights A, and below the cross-pieces B B carries a sprocket-wheel h' on one end and a cam-lever w upon the other end. Two cams w' are also mounted on said shaft at a sufficient distance apart to 85 lie beneath the end pieces H' of the twister-frame H. It is by means of the cams w' that the twister-frame is raised and lowered, thereby bringing the twisters into engagement with the horizontal wires a'. 90

The cam-lever w is adapted to engage a bent bar l', pivotally attached to the right cross-piece B. A rod L is suitably mounted inside the front uprights A and is provided with two arms M and a lever-arm M', all fixedly connected to the rod. The outer end of the lever-arm M' is connected with the bent lever l' by means of a rod N, which is pivotally attached to each. To the outer ends of the arms M are pivotally connected depending rods N', which are attached at their lower ends to a horizontal slotted bar L', said bar being provided with guides x at either end, said guides being adapted to slide vertically upon the guide-posts O, secured to the cross-pieces B B'. Said bar L' is provided with wire-holders y, having U-shaped slots in their depending ends, which are adapted to hold the horizontal wires a' in the slots in the twister-wheels while the twist is being 115 formed in the wires. This part of the machine is best seen in Fig. 5. The bar L', with the wire-holders y, is raised and lowered by means of the cam-lever w raising the bent lever l', which causes the rod N to lift the 120 lever-arm M', thereby slightly rotating the rod L, which in turn lifts the arms M, causing the rods N' to raise the bar L'. 125

The shaft P has mounted upon it three sprocket-wheels h'', the sprocket-wheels h'', the star-feed D', having the radial arms, and the open drum having the projecting portions z, which rise above the outside diameter of the sprocket-wheels h'' for the purpose of 130

lifting the woven fence out of the picket-holders and wire-guides. This shaft and its connection are best seen in Fig. 3. The reel Q, which may be of any suitable construction, is provided with a fixed shaft, one end of which is formed with a depression 2 and the other end with a clutch 3, as shown in Fig. 2. This reel is adapted to be supported at one end by means of a threaded bearing 4, mounted on the support C, which receives a set-screw 5, having a pointed end which enters the depression 2 in the shaft and turns therein. Said set-screw is adapted to be turned by hand and is provided with a lock-nut 6, which prevents its turning when the reel is in operation. Upon the opposite support C is a bearing 7, which supports one end of a short shaft R, the outer end of which is supported by a bearing 7', supported by braces 8 and 8'. The inner end of said shaft R is provided with a clutch 3', which engages with the clutch 3 upon the end of the reel-shaft, and thereby supports that end of the reel Q. A friction-disk 9, having a sleeve 10, is immovably secured to the shaft R, and a sprocket-wheel 11 is loosely mounted upon said sleeve, the length of said sleeve and thickness of sprocket-wheel being substantially the same. A friction-disk 9', without a sleeve, is placed next the opposite side of the sprocket-wheel 11, and is also secured to the shaft. From the disk 9' to the bearing 7' the shaft is threaded, as shown at 12, and is surrounded by a coil tension-spring 13, one end of which bears against the friction-disk 9' and the other end against the nut 6', by means of which the tension of said spring is regulated.

Figs. 17 and 18 illustrate the device whereby the woven fencing is held against lifting until it has passed a sufficient distance beyond the twisters. It consists of angular end frames 14, secured upon the cross-pieces B B. To these end frames are bolted the slotted bars L'', and hangers 15, bolted through the slots, and to the lower ends of said hangers are attached bars 16, rounded at both ends, beneath which the woven fencing slides. This prevents the fencing lifting out of the picket-holders and wire-guides until it has passed beyond the bars 16, when it is engaged by the projecting portions z of the open drum or cylinder, when it is disengaged and passed onto the reel Q. This action is best illustrated in Fig. 10. The above-described portion of the machine is not illustrated in Fig. 4.

Extending across the front end of the machine is a slotted bar S, to which are bolted the wire-tension devices 17, which tension the lower wires, and are illustrated in Fig. 7. The desired tension is obtained by turning the grooved spools 18, over which the wire passes, into the desired position, tightening the bolt 19, thereby securing the plate 20 against turning. A similar slotted bar S', to which are attached like devices to tension the upper wires, is attached to the cross-pieces B B near

their front ends, the upper wires first passing over the spools 18', mounted on the rod T, which is secured to the uprights A by means 70 of the brackets 21.

Near the front ends of the supports C' are bearings 7'', which support a shaft U, upon which are mounted three sprocket-wheels h''' of a size corresponding with the sprocket-wheels h''. These sprocket-wheels h'' and h''' each carry a sprocket-chain 22, to which are secured the bars V, carrying the picket-holders and wire-guides. A section of chain and one of the bars V are shown detached in 80 Fig. 6. These form an endless carrier passing over and under the machine. The picket-holders and wire-guides are formed by pins 23 and lugs 24, attached to the bars V. A shaft W, mounted between the cross-pieces 85 B B, carries three small sprocket-wheels 25 and serves to support the sprocket-chains at that point. This may be seen in Fig. 10. A short sprocket-chain 22' connects the sprocket-wheels h and h', and a sprocket-chain 22'' connects the sprockets 11 and h''.

In operation the band-wheel a is connected by a belt with a suitable power-shaft. The lever c' is thrown to cause the clutch c to engage the hub d of the band-wheel a, which 95 causes the shaft b to revolve, when the bevel-gear f on the end thereof will cause the loosely-mounted bevel-gears f' and f'' to revolve on the shaft D.

The small cog-wheel e, mounted on the shaft 100 b, meshes with the large cog-wheel e', which causes the shaft b' to revolve, and the small bevel f''', mounted on the end thereof and meshing with the large bevel-gear f''', causes the shaft E to revolve, and this revolves the 105 grooved wheel g, the trip-arm i, the operating-arms j, and the sprocket-wheel h, mounted thereon. The grooved wheel g imparts an oscillating motion to the bent lever m, pivotally mounted on the bar l, by reason 110 of the roller k' on the end thereof resting in the eccentric groove in the wheel g, thereby causing the sliding collar p to slide backward and forward upon the shaft D, the teeth r on said collar alternately engaging the teeth r' 115 on the bevels f' and f''. The collar p, sliding on a key in the shaft, will cause the shaft to revolve when the teeth on the collar engage the teeth on either bevel, as the bevels f' and f'' are constantly rotated by the bevel f. The 120 movement is so timed that when the shaft has revolved the requisite number of times that one of the rollers k'' on the trip-arm i will strike one of the ears t or t' on the eccentric wheel s, thereby checking the motion of the 125 shaft D and releasing the tension on the teeth r and r' and the grooved wheel g, simultaneously reaching a point that causes the lever m to slide the collar p out of engagement with the bevel-wheel. The collar p dwells slightly 130 in its movement between the bevels f' and f'', the shaft D in the meantime remaining stationary. The collar p, reaching its opposite limit, will engage the opposite bevel and

thereby again revolve the shaft D, but, as will be seen, in an opposite direction. The revolving of the shaft D revolves the small bevels v, fixedly mounted thereon, and they in turn mesh with the bevels v', mounted on the shafts I in the twister-wheel frame H, thus revolving them and thereby operating the twisters J, connected therewith. It will therefore be apparent that the wires passing through the machine will be given alternately a right and left twist.

The operating-arms j on either end of the shaft E revolve with the shaft and are so placed that the rollers k in each end of said arms will come in contact with one of the radial arms of the star-feed D', the rollers serving to reduce the friction of contact. This contact raises the radial arm until the roller passes it, and thereby slightly rotates the shaft P, upon which the star-feed D' is mounted, and at the same time brings the next radial arm into position, so the other end of the arm j will engage it in a like manner. It is thus that the endless carrier, composed of the sprocket-chains 22 and the bars V, is moved forward, stopping between each forward move long enough to allow the twisters to operate. The sprocket-wheel h on the shaft E imparts motion to the shaft K by means of the sprocket-chain 22' and the sprocket-wheel h' on said shaft K. The cams w, mounted on the shaft K, are so placed as to support the twister-wheel frame H and as the shaft revolves alternately raise and lower said frame, thereby bringing the twisters into contact with the wires a' while the twist is being formed and allowing it to drop away while the operating-arms are moving the endless carrier which carries the wires and pickets.

40 The cam-lever w on the end of the shaft K engages the bent bar l', which is connected with the lever-arm M' by the rod N, thereby causing the wire-holders y, secured to the slotted bar L', having the guides x, to be raised and lowered on the guide-posts O through the medium of the arms M and rod L. The vertical movement of slotted bar L is so timed that when the twisters are raised to the wires by the cams w' the said bar L' is lowered, with the holders y, upon the wires a', and when the twisters are lowered the bar is raised. The purpose of this part of the machine is to firmly hold the horizontal wires a' within the slots o' of the twisters.

55 The shaft P, which is rotated through the medium of the star-feed D' by the arms, has the sprocket-wheels h'', which carry the endless carrier, and the open drum having the projecting portions z of greater diameter than the sprocket-wheels h'', thereby causing said projecting portions to lift the woven fence out of the picket-holders and wire-guides as the endless carrier is carried on to and over the sprocket-wheels and the woven wire fencing is passed on to the reel Q. The reel Q is operated by means of a sprocket-chain 22'', which connects the sprocket-wheel h''' on the

shaft P with the sprocket-wheel 11, mounted between the friction-disks 9 and 9'. It is obvious that the reel Q will have to make a greater number of revolutions to reel a given number of feet of wire fence when the reel is nearly empty than when almost full, as the diameter of the roll constantly increases as the fence is wound upon it.

To regulate the speed of the reel, I provide the friction-disks, which allow the sprocket-wheel 11 to slip between the disks as the reel fills and the diameter of the roll increases, thereby insuring an even tension in the roll and at the same time preventing the reel from straining the machine by drawing too heavily on the wire. The tension of the disks 9 and 9' against the sprocket-wheel 11 is secured and regulated by the spring 13 and nut 6'. The distance between the horizontal wires a', between which the wire pickets are woven, is regulated by adjusting the tension devices upon the bars S and S', the picket-holders, the twisters, and the small bevels v and v', thereby allowing the machine to weave various designs of fencing. The horizontal wires a' are brought to the machine from suitable reels, the upper wires passing over the spools 18' and the tension devices 17, where they meet the lower wires, which come over the tension devices on the bar S at the front of the machine. The pickets are placed upon the lower wires, which lie between the wire-guides 23 on the bars V at the front end of the machine, by the attendant and are held from slipping by the picket-holders 24. As the endless carrier moves forward the picket is carried under the upper horizontal wire, and when it reaches the twisters it is firmly twisted between the upper and lower horizontal wires.

Having described my improved wire-fence machine, what I claim, and desire to secure by Letters Patent of the United States, is—

1. In a wire-fence machine of the class described, having a loosely-mounted power-wheel provided with a projecting hub adapted to engage a friction-clutch whereby the machine is set in motion, the combination of a pivotally-mounted bent lever M, having the forked end n, to engage a groove in a sliding collar p, and the roller k', mounted upon the other end and adapted to travel in an eccentric groove in the periphery of the wheel g, whereby an oscillating movement is imparted to said lever, for the purpose of sliding said collar p, upon its shaft, with the reversible twisting mechanism, the automatically-operated endless carrier, and the automatically-tensioned fence-winding reel, substantially as shown and described.

2. In a wire-fence machine of the class described, having a loosely-mounted band-wheel provided with a projecting hub, adapted to engage a friction-clutch whereby the machine is set in motion, the combination of the sliding collar p, having the teeth r, and the groove o, and the wheel g, having an eccentric groove

in its periphery, said wheel and collar being operatively connected by means of a pivoted bent lever m , with the automatically-operated wire-holding device, the automatically-operated endless carrier, the automatically-reversible wire-twisting devices, and the tensioned fence-winding reel, substantially as shown and described.

3. In a wire-fence machine of the class described, the combination of the operating-arms j , having the rollers k , adapted to engage the radial arms of the star-feed D' , and thereby automatically rotate the shaft P , carrying the endless carrier formed by the sprocket-chain 22, and the bars V , with the power-distributing mechanism, the alternately-reversible twisting mechanism, and the reeling mechanism, as shown and described.
- 20 4. In a wire-fence machine of the class described, the combination of the star-feed D' , having the radial arms adapted to be engaged by operating-arms j , provided with friction-reducing rollers k , with the power supplying and regulating mechanism, the alternately-reversible wire-twisting device, the wire holding and supporting devices, and the spring-tensioned fence-reel, as set forth.
- 25 5. In a wire-fence machine of the class described, having an alternately-reversible wire-twisting mechanism, the combination of the reel-tension device consisting of the shaft R , the friction-disks 9, and 9', the sprocket-wheel 11, the coil-spring 13, and the tension-nut 6', with the reel Q , the endless carrier comprising the sprocket-chains 22, the bars V , the wire-holding mechanism and the power supplying and distributing mechanism, substantially as shown and described.
- 30 6. In a wire-fence machine of the class described, the combination of the automatically-operated wire-holding mechanism, consisting of the rod L , the arms M , and M' , the connecting-rods N , and N' , the guide-posts O , the guides x , the slotted bar L' , and the wire-holders y , with the cam-lever w , mounted on the shaft K , the alternately-reversible twisting mechanism, the endless carrier, the reel-tensioning device and the power connecting and distributing mechanism, as shown and described.
- 35 7. In a wire-fence machine of the class described, having a power connection and suitable power-distributing mechanism, the combination of the pivotally-mounted frame H , carrying twisters J , the shafts I , and the small bevel-wheels v' , with the automatic reversing mechanism, consisting of the bevel-wheel f , on the power-shaft b , the bevel-wheels f' , and f'' , and the sliding collar p , on the shaft D , the pivotally-mounted lever m , the eccentrically-grooved wheel g , on the shaft E , and the cams w' , mounted on the shaft K , substantially as set forth.
- 40 8. In a wire-fence machine of the class described, provided with an automatic alter-

nately-reversible wire-twisting mechanism, the combination of the endless carriers consisting of the sprocket-chains 22, and the bars v , provided with the wire-guides 23, and the picket-holders 24, with the sprocket-wheels h , and h'' , the open drum having the projecting portions z , the wire-tension devices 17, and the reel Q , substantially as shown and described.

75 9. In a wire-fence machine of the class described, having an automatically-operated reversible wire-twisting mechanism, the combination of the eccentric wheel s , mounted on the shaft D , having ears t , and t' , with the trip-arm i , mounted on the shaft E , having the rollers k'' , on the ends thereof, said rollers k'' , adapted to engage said ears t , and t' , as set forth.

85 10. In a wire-fence machine of the class described, having an automatically-operated endless carrier, an alternately-reversible wire-twisting mechanism, and means for feeding and reeling the wire and fencing, the combination with the wire-holders y , of the device 90 whereby the woven fencing is prevented from lifting, consisting of the end frames 14, the slotted bars L' , the hangers 15, and the bars 16, having rounded ends, as shown and described.

95 11. The combination in a wire-fence machine of the class described, of the reversible wire-twisting mechanism, with a pivotally-mounted frame carrying the wire-twisting mechanism, and adapted to be raised and lowered by means of cams mounted upon a shaft beneath it, thereby causing the wire-twisters mounted on said frame to alternately engage and release the horizontal wires, between which the pickets are being twisted, 105 substantially as set forth.

12. A wire-fence machine of the class described, having an automatic reversible actuated wire-twisting mechanism, in combination with the means for carrying the wire 110 through the machine consisting of the endless carrier and the sprocket-wheels h'' , mounted on the shaft P , in conjunction with the sprocket-wheels h''' , and 25, and the arms j , engaging the star-feed D' , by which said shaft 115 P , is rotated, substantially as set forth.

13. The combination in a wire-fence machine of the class described, of the tension devices 17, consisting of the grooved spools 18, the tightening-bolt 19, and the securing-plate 20, bolted to the slotted bars S , and S' , with the automatically-operated endless carrier, consisting of the sprocket-chains 22, and the bars V , having the wire-guides 23, and the picket-holders 24, as set forth.

125 14. In a wire-fence machine of the class described, the combination of the reel Q , supported by the set-screw 5, the end of which enters the depression 2, in the reel-shaft on one end, and by the clutch 3, which enters 130 the clutch 3', on the other end, with the reel-tensioning device, consisting of the friction-

disk 9, having the sleeve 10, fixedly mounted on the shaft R, the sprocket-wheel 11, mounted on the sleeve 10, the friction-disk 9', mounted on the shaft R, and adapted to be held 5 against the sprocket-wheel 11, by means of a coil-spring 13, the tension of which is regulated by the set-nut 6', substantially as shown and described.

15. In a wire-fence machine operated by power other than hand-power, and having an automatically-operated endless carrier, a series of alternately-reversible wire-twisters and a tensioned wire-fence reel, the combination of the shaft K, having the cams w, 15 whereby the twister-frame H, is raised and lowered, and the cam-lever w, with the automatically-actuated wire-holding devices consisting of the holders y, the slotted bar L', the guide-post O, the guides x, the rod L, the 20 cams M, and M', and the connecting-rods N, and N', as shown and described.

16. In combination in a wire-fence machine of the class described, the band-wheel a, having the projecting hub d, loosely mounted on the shaft b, the cog-wheel e, and bevel-gear f, fixedly mounted on said shaft; the shaft b', carrying the large cog-wheel e', and the bevel-gear f'''; the shaft P, carrying the star-feed arms, the open drum, the sprocket-wheels h'', 25 and the sprocket-wheel h'''; the shaft D, carrying the eccentric wheel s, having the ears 30

t, and t', the friction-block F, the loosely-mounted bevel-gears f', and f'', the sliding collar p, and the fixedly-mounted bevel-gears v; the shaft E, carrying the trip-arm i, the operating-arms j, having the rollers k, the eccentrically-grooved wheel g, the large bevel-gear f''', and the sprocket-wheel h; the shaft K, carrying the sprocket-wheel h', the cams w', and the cam-lever w; the shaft U, carrying the sprocket-wheels h'''; the shaft W, carrying the small sprocket-wheels 25; the bent lever M, pivotally mounted on the bar l; the twister-frame H, carrying the twisters J, and the shaft F, upon which are mounted the bevel-gears v'; the wire-tension devices 17, mounted on the slotted bars S, and S'; the reel Q, and the reel-tension consisting of the friction-disks 9, and 9', the spring 13, the regulating-nut 6', and the sprocket-wheel 11, mounted 50 on the sleeve 10, of the disk 9, said sprocket-wheel 11, being connected with the sprocket-wheel h''', by the sprocket-chain 22', all substantially as and for the purpose shown and described.

55 In testimony whereof I affix my signature in presence of two witnesses.

JOHN W. DWIGGINS.
